UNITED STATES PATENT OFFICE.

FRED L. BAER, OF LA GRANGE, ILLINOIS, ASSIGNOR TO AUTOMATIC ELECTRIC COMPANY, OF CHICAGO, ILLINOIS, A CORPORATION OF ILLINOIS.

CALLING DEVICE.

Substitute for abandoned application Serial No. 525,931, filed December 30, 1921. This application filed May 13, 1922. Serial No. 560,633.

To all whom it may concern:

Be it known that I, FRED L. BAER, a citizen of the United States of America, and a resident of La Grange, Cook County, and 5 State of Illinois, have invented certain new and useful Improvements in Calling Devices, of which the following is a specification.

The present invention relates in general 10 to calling devices or impulse senders for automatic telephone systems, and the object of the invention is to provide a novel and improved number plate which renders calling devices of the above character better 15 adapted for use in large systems.

The invention is illustrated in the accompanying drawings, in which Fig. 1 shows a front view of a calling device equipped with the improved number plate, while Figs. 20 2 and 3 show the number plate of Fig. 1 and a modification thereof, respectively.

In mechanical construction the calling device shown may be of the type shown and described in the book, Automatic Telephony, 25 by Smith and Campbell, second edition, pages 40 and 41. As is well known, a calling device of this kind is provided with a finger hole dial which is operable in accordance with the digits in a called telephone 30 number to transmit corresponding series of impulses over the line to the exchange, in order to operate a plurality of serially related automatic switches to establish the desired connection.

In the beginning, such calling devices had 35 the finger holes designated by numerals only, and the telephone numbers as listed in the directory were composed solely of numerals, as for example, No. 4567. Later on, 40 and especially in large systems, it became the practice to prefix one or more letters to the digits of the directory numbers, forming so called composite numbers such as A 4567.

At the same time, of course, letter designations 45 were added to the calling device number plates and each finger hole was marked with a numeral and also with a letter. The use of one or more letters in place of the corresponding numerals made it easier for 50 the subscribers to remember the telephone numbers.

A further modification or improvement has been brought about by the introduction

of automatic systems in very large cities, 55 where the telephone population is so large as to require the use of as many as seven digits in the telephone numbers. Such large systems are made up of a large number of different offices or exchanges, and it has been proposed to use the first three letters of the 60 exchange name in place of the first three digits of each telephone number. The composite numbers thus formed are usually suggestive of the exchanges to which the subscribers are connected and consequently are 65 easily remembered. In order to prevent confusion resulting from the subscribers calling too many letters, the first three letters of 70 each exchange name, which are the only ones which have to be dialled, are printed in heavy type, as for example, MONroe 3200, or KILDare 9467.

The spelling of the exchange names, or 75 rather of parts of them, requires the use of all letters of the alphabet except Q and Z, which are not usually found in the names of exchanges. According to known practice, these letters are arranged on the number plate with the letters ABC associated with the digit 2, letters DEF associated with the digit 3, letters GHI associated with the digit 4, and so on, which brings letters 80 WXY in the finger hole allotted to the digit 9, it being understood that letters Q and Z are omitted.

The above described arrangement for a calling device has been considered satisfactory, and it has the advantage that there is only one vowel in each finger hole, which makes it possible to spell a maximum number of exchange names. Another point, 90 usually considered an advantage, is that none of the three letter combinations, as ABC, spell an ordinary word. I have discovered 95 however, a great disadvantage, one which is inherent in the numbering scheme employed, and which is entirely obviated by the present invention. The difficulty arises from the fact that the letter I is in the same finger hole with the digit 4, while the letter O is in the same hole with the digit 6. Letters I and O are very similar to the digits 1 and 0 (zero), respectively, and a subscriber in calling I, for example, is liable 100 to call the digit 1 instead, which causes only 105 one impulse to be transmitted instead of 4

and results in a wrong number. The mistakes thus made are natural, and constitute a serious defect in the system.

A new method of numbering or assigning the letters has been devised, therefore, which is systematic, which retains all the good features of the old plan, and which at the same time completely eliminates the defects pointed out above. According to the new scheme, and referring especially to Fig. 2 of the drawings, I begin by assigning the letter A to the finger hole occupied by the digit 2, and assign the succeeding letters B, C, etc., to the next higher digits 3, 4, etc., 15 going around the number plate in a counter-clockwise direction until the letter I is reached. This letter is not assigned to the digit 0 (zero), but is assigned instead to the digit 1, and the numbering then continues as 20 before, letter J being assigned to the digit 2, letter K to the digit 3, etc., until the letter O is reached. At this point enough digits are skipped to bring the letter O in the same finger hole with the digit 0 (zero), 25 whereupon the numbering continues as before until the letters are exhausted, it being noted, however, that letters Q and Z are omitted. This brings the last letter Y in the finger hole occupied by the digit 9. Of course if it is desired one or both of the letters Q and Z could be included, as there is space available in the last and first finger holes.

It will be seen that according to the foregoing plan the letters are assigned to the finger holes in regular order, the circuit of the dial being repeated until all the required letters are located, with the exception that when letters I and O are reached 35 enough finger holes are passed by to place these letters in the finger holes occupied by digits 1 and 0 (zero), respectively, which are the ones they most nearly resemble. By this procedure all trouble due to errors of 40 the subscribers in calling the letters or digits particularly mentioned is avoided, for each of these letters is in the same finger hole with the corresponding digit and it makes no difference therefore whether the 45 subscriber calls the letter or the digit, as the same number of impulses will be transmitted in either case.

The number plate marked according to the above method is perhaps the preferred form, and is especially so in case the letters are printed in the directory in one color and the numerals in another color, as may be done, or in case the type used is substantially different in the case of the letters and numerals. It may happen, however, that only one color is used, and that the style of the type is such that letters I and O are nearly or exactly identical with numerals 1 and 0 (zero), respectively. 60 65 In this case the number plate may be like

the one shown in Fig. 3, in which a single character is used to designate the letter I and the numeral 1, and a single character for designating the letter O and the numeral 0 (zero).

What I claim is:

1. A calling device for automatic telephone systems having a rotatable finger hole dial, impulse sending mechanism variably controlled by the dial in accordance with the finger hole used, digit designations for the finger holes, and letter designations for the finger holes also, the said letter designations being assigned to the holes according to a method which brings letters O and I in the same holes as the digits 0 and 1, respectively, thereby rendering it immaterial so far as the number of impulses transmitted is concerned whether the subscriber calls the said letters or the said digits.

2. As an article of manufacture, a number plate for automatic calling devices, said number plate having characters representing digits and other characters representing letters, each letter being associated with a digit, and the letters O and I being associated with the digits 0 and 1, respectively.

3. As an article of manufacture, a number plate for automatic calling devices, said number plate having characters representing the ten digits 1 to 0, inclusive, and all the letters of the alphabet except the letters Q and Z, there being one or more letters associated with each digit, and the letters O and I being associated with the digits 0 and 1, respectively.

4. As an article of manufacture, a number plate for automatic calling devices, said number plate having a plurality of characters representing digits, a second plurality of characters representing letters, and a third plurality of characters which represent both letters and digits.

5. As an article of manufacture, a calling device number plate having a plurality of number positions corresponding to the finger holes of a calling device dial, said positions being occupied by characters corresponding to the digits 1 to 0, inclusive, the positions which are occupied by the digits 1 and 0 being occupied also by characters representing the letters I and O, respectively, and each of the other positions being occupied also by characters representing one or more of the remaining letters.

6. The method of assigning letters of the alphabet to a number plate for a calling device, which consists in allotting the letter A to the digit 2 and in allotting succeeding letters to the next higher digits in order until the letter I is reached, which is allotted to the digit 1, in allotting the letters following the letter I to the digits follow-

ing the digit 1 in regular order until the letter O is reached, which is allotted to the digit 0, and in then allotting the remaining letters except letters Q and Z to digits 5 in regular order beginning with the digit 1.

7. The method of assigning letters of the alphabet to the numbered finger holes of a calling device, which consists in assigning the letters to the several finger holes 10 in regular order, the process being repeated

as often as is necessary to locate all the letters required, and which consists further in passing by sufficient finger holes when the letters I and O are reached to locate these letters in the finger holes occupied by the digits 1 and 0, respectively. 15

In witness whereof, I hereunto subscribe my name this 9th day of May, A. D., 1922.

FRED L. BAER.
